[57] CLAIM

The ornamental design for a router, as shown and described.

DESCRIPTION

FIG. 1 is a front and top perspective view of a router showing my new design;

FIG. 2 is an enlarged front elevational view thereof;

FIG. 3 is an enlarged rear elevational view thereof;

FIG. 4 is an enlarged right side elevational view thereof;

FIG. 5 is an enlarged left side elevational view thereof;

FIG. 6 is an enlarged top plan view thereof; and

FIG. 7 is an enlarged plan view thereof;

The power cord is shown broken-away in the views to indicate indeterminate length.

FIG. 1FIG. 4

FIG. 5

FIG. 6

FIG. 7
